ATTORNEY

UNITED STATES PATENT OFFICE.

WILLIAM W. DUSENBURY, OF BROOKLYN, NEW YORK.

MANUFACTURE OF ICE.

SPECIFICATION forming part of Letters Patent No. 240,396, dated April 19, 1881.

Application filed September 17, 1880. (No model.)

To all whom it may concern:

Be it known that I, WILLIAM W. DUSENBURY, of Brooklyn, in the county of Kings and State of New York, have invented a new and useful Improvement in the Manufacture of Ice, of which the following is a specification.

My invention consists, first, of a house or receptacle for the formation, preservation, and storage of ice, having the walls in horizontal sections arranged to be built up to inclose the successive layers or sheets of water without interfering with the free exposure of the surface of the water to the freezing atmosphere, and adapted to form non-heat-conducting and permanent walls for inclosing the body of ice and preserving it against the action of the exterior atmosphere; secondly, it consists in an outer or inclosing house or shell, surrounding the ice house or receptacle, and provided with non-conducting walls or curtains adapted to be readily adjusted to expose the inner ice house or receptacle, and the water therein to the action of the cold exterior air, or to shut in the said house or receptacle and thereby prevent the admission of heat to the interior of the ice-house; lastly, the invention consists of details of construction which will be fully described farther on in the specification.

In the accompanying drawings, Figure 1 represents a side elevation of my improved ice house or receptacle. Fig. 2 represents a vertical section of the same, taken on line $x x$ of Fig. 1. Fig. 3 represents a horizontal section of the house, taken on line $y y$ of Fig. 1.

Referring to the drawings, A represents the floor or bottom of the house or receptacle, which may be made in any suitable manner to hold water and serve as a non-conductor of heat.

B represents uprights or posts rising from the floor A. These posts are provided with double parallel grooves $a a$, which may be rabbed into the posts, or formed of channel-iron fixed to the posts, as may be preferred.

The house or receptacle may be divided into as many floors or compartments as may be desired by horizontal partitions or floors. In the drawings two such compartments, D D', are represented, divided by a partition or floor, E, which may be arranged with air-spaces b , to make it a non-conductor of heat, or it may be made non-conductive in any other suitable

manner. When the receptacle or house is divided into compartments, as shown, the floors or partitions may be permanently fixed to the posts B at regular distances apart, forming compartments of the same size, if required, or they may be fixed at irregular distances, forming compartments of different sizes and capacities, if preferred; but if it is desired to have the compartments of varying size and capacity the floors or partitions may be unconnected with the posts and supported by screws, weights, or other suitable devices that will permit the said floors or partitions to be raised and lowered to vary their distances from each other, and from the floor of the house or receptacle. The latter method is the preferable one, as, in case the compartment cannot be filled with ice, from any cause, the floors or partitions may be lowered to the top of the ice in the compartments below, whereby currents of air are excluded and the ice protected against exposure. This arrangement is also advantageous on account of the facility it offers for getting the ice out of the house, as when the lower compartments are emptied those above can be lowered one after the other and the ice taken out close to the ground. The division of the ice house or receptacle into compartments also facilitates the manufacture of the ice, as will appear when the operation is described.

The top F of the house or receptacle may be a frame-work connecting the tops of the posts B, or it may be a double ceiling, similar in construction to the floors or partitions E.

The walls of the house or receptacle are intended to be in horizontal sections adapted to be taken out and replaced without difficulty. By preference these sections may be composed of planks or plates I, of any suitable material. The ends of the planks or plates should be adapted to form a water-tight connection with the grooves $a a$, and their edges may be matched for the same purpose, so that when the sections are put in place the walls G will be water-tight; but to insure water-tight joints packing or calking may be employed. The spaces f between the inner and outer walls may be filled in with any suitable non-conducting material as the sections are built up.

The outer house or inclosing-shell should be of sufficiently large dimensions to leave work-

ing room between its inner walls and the walls of the inner house or receptacle. The outer house may be made in the following manner: Posts or uprights L rise from the floor of the ice-house and support a roof or top, M, which may be made impervious to heat by double walls with an air-space between, or in any other suitable manner. The uprights are provided with double grooves g g.

10 N N represent curtains which run in the grooves g g. These curtains may be made of iron or wooden slats strung on wires or bands, so as to roll up on the barrels O, or they may be made of paper, felt, or any other suitable material having sufficient strength and imperviousness to heat for the purpose. The curtains are supported by the barrels or rollers O, which may be provided with cranks to roll up the curtains, or they may be provided with 15 springs to automatically roll up and unroll the curtains when they are raised and lowered, or other suitable power may be employed.

10 The object of having the walls of the outer house or shell adapted to open and shut is to 25 permit the interior house or receptacle to be inclosed for the purpose of excluding heat and currents of air, and protect it against changes in the exterior atmosphere, and also to permit the house or shell to be completely opened 30 when the water is to be exposed to a freezing atmosphere and slight air-currents during the formation of the ice in the receptacle. I do not, however, confine myself to the use of rolling curtains for this purpose, as doors, sliding 35 walls, or removable walls may be substituted for them, or any other arrangements that will permit the inner house or receptacle to be quickly and easily inclosed and thrown open at will.

40 In Fig. 1 the curtains are represented as part way down. In Fig. 2 they are represented as closing up the sides of the house.

The water from which the ice is formed may be supplied from a stand-pipe, main, by pumping, or in any other convenient manner.

45 The operation of the invention is as follows: When there is sufficient cold to produce ice the curtains or side walls, N, are raised or opened to admit the freezing atmosphere. The 50 sectional walls I, which should be of a depth that experience may dictate to be most available, are removed, with the exception of one or more of the bottom ones, as shown in Fig. 1, so as to leave a space inclosed by the sections, which 55 should not, however, be so high as to protect the water within from the most favorable action of the freezing atmosphere: Water is now run into the space inclosed by the sections to a depth adapted to the degree of cold prevailing, the object being to obtain a sheet or layer of water that will freeze solid as quickly as possible. This sheet or layer is allowed to freeze, then another quantity of water is run on top of the sheet of ice formed by the first sheet of water, so as to form a superimposed sheet, and this is allowed to freeze in like manner as the first. This is continued until the space inclosed

60 by the sections is nearly filled, when other sections are added, as indicated by the dotted lines in Fig. 1, and the process is continued until 70 the ice-house or compartment thereof (if compartments are employed) is filled. The effect of this process is to form a solid body of ice in the house entirely free from snow, and of a purity equal to that of the water from which it is 75 formed, and this is accomplished without the waste, expense, and trouble ordinarily expended in gathering ice and storing it. Owing to the compactness of the body of ice obtained in this manner it is much easier preserved. 80

By having the ice-house divided into compartments the freezing operation can be carried on in all the compartments simultaneously, and thereby the work of filling the house can be greatly expedited. For example, while a 85 layer of water is being frozen in one compartment, D, another layer may be freezing in compartment D', and so in every compartment in the house.

90 As the sections I are placed in position to form the walls G, the spaces f between the sections may be filled in with any suitable non-conducting material, or the material may be put in after the sections are all in place. The space between the curtains or walls N N of the 95 exterior house may also be filled in, when the curtains are drawn down permanently, with a suitable material, and suitable weather-strips may be placed at the junction of the curtains with the uprights or frames, to prevent the admission of air. 100

Any one or more of the curtains or walls N may be provided with a suitable door to give entrance to the ice-house, and the sectional walls G of the interior ice house or receptacle 105 may be arranged in any convenient manner to allow the ice to be taken out without trouble.

I do not confine myself to the use of the grooved uprights as a frame-work for the houses, as any suitable frame-work adapted to support 110 the peculiar walls of the houses may be substituted; neither do I propose to have the exterior house a permanent part of the ice-house, as the latter may be built alone and the other built around it afterward, if it is required. 115

Some of the compartments—say, alternate ones—may be used as refrigerating rooms or chambers for the reception and storage of perishable articles, &c.

I claim—

1. As an improvement in the manufacture of ice, a house or receptacle composed of a suitable frame-work, and non-heat-conducting walls G, formed of removable horizontal sections I, adapted to form the permanent inclosing-walls 125 for the ice, and to preserve the same against the action of the external atmosphere, substantially as herein shown and described.

2. In combination with a suitable frame-work and non-heat-conducting walls G, composed of removable horizontal sections I, the floor or partition E, to divide the ice-house into compartments, each of which is adapted for the formation of ice from natural cold, and for the 130

storage and preservation of the ice when formed in a solid body, substantially as herein shown and described.

3. An exterior house or inclosure for ice houses or receptacles composed of a suitable frame-work, in combination with walls or curtains N, arranged for opening and closing, for the purpose of admitting cold air to the inclosed ice-house or excluding warm air therefrom, as may be required, substantially as described and shown.

4. In combination with an ice house or receptacle adapted for making, storing, and pre-

serving ice, an exterior inclosing house or shell composed of a suitable frame-work and side walls, arranged to be opened for the admission of cold air, and to be closed for excluding warm exterior air, and preventing the escape or radiation of the cold within the inclosing house or shell, substantially as herein described and shown.

WILLIAM W. DUSENBURY.
